US00D803196S

(12) **United States Design Patent** (10) Patent No.: **US D803,196 S**
(45) Date of Patent: **** Nov. 21, 2017**

(54) **DUAL FIN ANTENNA**

(71) Applicant: **TAOGLAS GROUP HOLDINGS**,
Enniscorthy (IE)

(72) Inventors: **Ronan Quinlan**, Dublin (IE); **Dermot O'Shea**, La Jolla, CA (US)

(73) Assignee: **TAOGLAS GROUP HOLDINGS LIMITED**, Enniscorthy (IE)

(**) Term: **15 Years**

(21) Appl. No.: **29/540,619**

(22) Filed: **Sep. 25, 2015**

(51) LOC (10) Cl. **14-03**

(52) U.S. Cl.

USPC **D14/230**

Cecily Anne O'Regan

(57) **CLAIM**

The ornamental design for a dual fin antenna, as shown and described.

DESCRIPTION

FIG. 1 is a perspective view of a dual fin antenna;
FIG. 2 is a right side view of a dual fin antenna;
FIG. 3 is a left side view of a dual fin antenna;
FIG. 4 is a front view of a dual fin antenna;
FIG. 5 is a back view of a dual fin antenna;
FIG. 6 is a top view of a dual fin antenna; and,
FIG. 7 is a bottom view of a dual fin antenna.
The broken lines are included for illustrative purposes only
and form no part of the claimed design.

1 Claim, 7 Drawing Sheets
